ARRANGEMENT FOR ADAPTING THE SPEED OF TAKE-UP TO THE SPEED OF FEED IN PRODUCING THREAD OR TAPE MATERIAL WITH ORIGINALLY LOW MECHANICAL STRENGTH

Ture A. Ljungberg, Stuvsta, Sweden, assignor to
Allmanna Svenska Elektriska Aktiebolaget,
Västerås, Sweden, a Swedish corporationApplication September 22, 1949, Serial No. 117,214
In Sweden September 28, 1948

3 Claims. (Cl. 18—8)

1

In producing some thread or tape material the mechanical strength when leaving the machine is still so low that a pulling, for instance for rolling up on drums or cylinders will affect the shape. First after having been cooled to a lower temperature, dried, or has been given in some other manner an increased mechanical strength, a mechanical stress should be allowed. But even now great care ought to be taken. The rate of "take-up" is continuously increasing with the diameter of the roll which is being built up, while the rate of delivery from the machine remains constant.

This invention relates to an arrangement for adapting the speed of take-up to the speed of feed, especially useful for the production of thread or tape material with low original mechanical strength. The object of this arrangement is that the thread or tape material is deviated from its natural straight path on a point, where its strength has already been increased by means of revolving wheels or rolls over and/or between which the material is pulled, the axes of such wheels or rolls being so arranged as to enable a lateral motion of the wheels or rolls. An increase of mechanical tension in the thread or tape material will cause the lateral motion of the above mentioned wheels or rolls, and a braking device influenced by this motion affects the rate of take-up so as to always adapt this rate to the rate of delivery of the machinery.

Arrangements according to the invention are illustrated in the accompanying drawing, wherein

Figures 1 and 2 show two projections of an embodiment suitable for thread material with good flexibility.

Figures 3 and 4 show the same for another embodiment.

Figures 5 and 6 show embodiments suitable for tape material and for less flexible thread material.

Referring to Figures 1 and 2 an extrusion machine e. g. the outlet of a lead press is denoted 1. From here comes the extruded material or the thread 2. Via the inlet 3 it is led into a groove in a brake-shoe 5 having the shape of a bow and pivoted on a bearing at the point 4. From the brake-shoe 5 the thread is laid around the wheel 6, laterally movable with respect to the brake-shoe 5. If there is a pulling stress in the thread at the outlet 7 where the thread is taken up on a reel not shown in the drawing, the wheel 6 and the brake-shoe 5 will approach each other with braking power as a result. The

magnitude of the braking power depends upon the magnitude of the tension, and a maximum of braking power is obtained when the wheel is clamped, the pulling power then having to overcome the friction of the thread against the whole surface from the outlet 7 to the inlet 3.

If the thread 2 is extruded too rapidly from the extrusion machine 1 no noteworthy braking power due to the brake-shoe 5 will appear, whereas a pulling at the outlet 7 and a small braking power at the inlet 3 will cause a great braking power resulting from an approach of the wheel 6 to the brake-shoe 5.

At a certain magnitude of pulling power the friction of the brake-shoe 5 increases so as to cause a braking power upon the wheel 6 resulting even in a friction between the thread 2 and wheel 6 and the remaining pulling power in the thread 2 at the outlet of the extrusion machine is very low with respect to the power at the outlet of the braking device.

By means of letting the thread 2 make several turns around the wheel 6 the braking power can be increased to any desired value. This is shown in the Figures 3 and 4 having the same indices for the parts corresponding to those of the Figures 1 and 2. The braking effect between the brake-shoe 5 and the wheel 6 will in this case be maintained by a separate brake drum 8 fastened to the centre of the wheel 6, the brake drum being affected by a brake-shoe 9 in conjunction with the bow 5. The wheel 6 can be substituted by one or several rolls for wider tapes or by one or several wheels, in order that the tape will not have to be bent at such large angles.

Such an arrangement is shown in Figure 5, where the tape 2 from the extrusion machine 1 is led over the roll 10 between the rolls 11, so that the tape is deviated from its straight path. A pulling power at the outlet 12 will press the rolls 10, 11 against their braking devices 13, the effect of braking and friction between tape and rolls being produced as previously described.

By means of several wheels or rolls the effect can be increased to any desired extent.

There are different means available to increase the coefficient of friction of the surfaces of the wheels or rolls, and in some cases even a sharp-toothed surface will be allowed.

An increase of the braking effect of the braking drums can be obtained by means of levers or some other arrangements if the desired friction has got to exceed the one normally obtained between the thread or tape material and the wheels or rolls.

I claim as my invention:

1. An auxiliary device for a machine manufacturing a thread or tape by extruding a material having a low tensile strength when the material leaves the extrusion means and which strength increases rapidly therefrom, comprising an extrusion mouth-piece, a roll for receiving the extruded material, a braking clutch for said roll, and means whereby tension in the extruded material causes the clutch to engage said roll, the said receiving roll and the extrusion mouth-piece being spaced from each other to the extent necessary to permit the intervening extruded material to attain sufficient mechanical strength to withstand the pull when it reaches the roll.

2. An auxiliary device for a machine manufacturing a thread or tape by extruding a material having a low tensile strength when the material leaves the extrusion means and which strength increases rapidly therefrom, comprising an extrusion mouth-piece, a pivoted roll to receive the extruded material, a brake-shoe for said roll, and means whereby said brake-shoe is engaged by said material and is actuated thereby before such material engages said roll, the said receiving roll and the extrusion mouth-piece being spaced from each other to the extent nec-

essary to permit the intervening extruded material to attain sufficient mechanical strength to withstand the pull when it reaches the roll.

3. An auxiliary device for a machine manufacturing a thread or tape by extruding a material having a low tensile strength when it leaves the extrusion mouth-piece and in which the said strength increases rapidly therefrom, comprising a pivoted roll receiving the extruded material, a brake-shoe movable in relation to said roll, and means whereby the extruded material is conducted from the mouth-piece and is caused to slide over said brake-shoe in direct contact therewith before it engages the said roll and whereby said shoe is forced into braking engagement with said roll by the tension in the extruded material in engagement therewith.
